DESIGN FOR A COMBINED PORTABLE ROTISSERIE AND BARBECUE STAND

Charles A. Robinson, Los Angeles, Calif.

Application May 31, 1939, Serial No. 85,258

Term of patent 7 years

To all whom it may concern:

Be it known that I, Charles A. Robinson, a citizen of the United States and a resident of the city of Los Angeles, in the county of Los Angeles and State of California, have invented a new, original, and ornamental Design for a Combined Portable Rotisserie and Barbecue Stand, of which the following is a specification, reference being had to the accompanying drawing, forming part thereof, in which:

Figure 1 is a perspective view of a combined portable rotisserie and barbecue stand showing

my new design. The top shelf is shown broken away for convenience of illustration to show the interior and back of the article. It is understood that the other portion of the shelf is substantially like that shown.

Fig. 2 is a side elevational view thereof.

I claim:

The ornamental design for a combined portable rotisserie and barbecue stand, substantially as shown and described.

CHARLES A. ROBINSON.
